UNITED STATES PATENT OFFICE

CHARLES F. PEARCE, JR., OF CHICAGO, ILLINOIS, ASSIGNOR TO BURTON-DIXIE CORPORATION, OF CHICAGO, ILLINOIS, A CORPORATION OF ILLINOIS

DESIGN FOR TEXTILE FABRIC

Application filed August 7, 1930. Serial No. 36,587. Term of patent 14 years.

To all whom it may concern:

Be it known that I, CHARLES F. PEARCE, Jr., a citizen of the United States, residing at Chicago, in the county of Cook and State of Illinois, have invented a new, original, and ornamental Design for Textile Fabric, of which the following is a specification, reference being had to the accompanying drawing, forming part thereof.

The figure is a plan view of a fragment of a piece of textile fabric showing my new design which consists of the combination of the body or ground, and the medallion-like configuration overlying same.

I claim:

The ornamental design for textile fabric, as shown and described.

CHARLES F. PEARCE, JR.
